UNITED STATES PATENT OFFICE.

HANS O. KEFERSTEIN, OF NEW ORLEANS, LOUISIANA.

BOILER.

No. 908,574.

Specification of Letters Patent.

Patented Jan. 5, 1909.

Application filed October 5, 1908. Serial No. 456,211.

To all whom it may concern:

Be it known that I, HANS O. KEFERSTEIN, a subject of the Emperor of Germany, residing at New Orleans, in the parish of Orleans and State of Louisiana, have invented certain new and useful Improvements in Boilers; and I do hereby declare the following to be a full, clear, and exact description of the invention, such as will enable others skilled in the art to which it appertains to make and use the same.

This invention relates to steam boilers provided with tubes for fire and for water; and it consists in the novel construction and combination of the parts hereinafter fully described and claimed.

In the drawings, Figure 1 is a vertical section of a steam boiler. Fig. 2 is a cross-section taken on the line $x-x$ in Fig. 1. Figs. 20 3 and 4 are also vertical sections showing modifications of the boiler shown in Fig. 1.

A and B are two chambers which are separated from each other by a suitable partition or partitions.

25 C is a fire-grate at the lower part of the fire-chamber A, and D is a chimney at the upper part of the smoke-chamber B.

E is the bridge-wall which forms the lower part of the partition between the chambers 30 A and B, the upper part of the partition being formed by the headers of the boiler as hereinafter fully described.

The boiler is divided into two sections F and G, each section having its own fire-tubes and water-tubes I. The heating section F of the boiler is arranged in the smoke-chamber B, and it is provided with a header J. The other section G of the boiler is arranged in the fire-chamber A, and it is provided with a header K. The two headers J and K are arranged over the bridge-wall E at a little distance apart, so that an intermediate chamber L is formed between them, and these two headers and the chamber L 45 form the upper part of the partition which separates the chambers A and B.

M is a plate which supports the rear end portions of the water-tubes in the smoke-chamber; and N is a plate which supports the front ends of the water-tubes in the fire-chamber.

O is a partition plate which separates the header J into two compartments P and Q.

R is a partition plate which separates the header K into two compartments S and T. A receiver U is arranged above the header K,

and the partition R extends into it nearly to its top, so that the receiver is connected with the compartments S and T.

Y is an inlet pipe for cold water connected to the bottom part of the compartment P.

W is a pipe which connects the two compartments Q and T at their bottom ends.

V is a steam pipe which connects the top of the compartment Q with the steam space 65 of the receiver U. A steam outlet or delivery pipe 2 is connected to the receiver U.

The water-tubes of the section F are connected at one end with the compartment P, and their other ends are supported by the 70 plate M, and are closed by caps 3. The fire-tubes of the section F are arranged inside the water-tubes, and pass through holes in the caps 3 and in the header J, so that the intermediate chamber L is connected with the 75 smoke-chamber B. The upper side of each water-tube of the section F is connected with the compartment Q by means of a tubular connection 4. A longitudinal partition 5 is provided at the header end portion of the 80 section F between its fire-tubes and water-tubes.

The water-tubes of the section G are connected at one end with the compartment T, and their other ends are supported by the 85 plate N, and are closed by caps 6. The fire-tubes of the section G are arranged inside the water-tubes, and pass through holes in the caps 6 and in the header K, so that the intermediate chamber L is connected with 90 the fire-chamber A. The upper side of each water-tube of the section G is connected with the compartment S by a tubular connection 7, and a longitudinal partition 8 is provided at the header end portion of the 95 section G between each fire-tube and the water-tube which incloses it.

The products of combustion from the grate pass in the direction of the arrows 10 between the water-tubes of section G, 100 through the fire-chamber A and over the plate N; thence through the fire-tubes of both sections and the intermediate chamber, through the smoke-chamber and under the plate M to the chimney. The cold water 105 enters the compartment P by the pipe Y, and passes through the water-tubes of section F in the direction of the arrows 11; thence downward through compartment Q, through the pipe W, and upward through 110 the compartment T, and through the water-tubes of section G. The steam generated

in section G passes from its water-tubes, through the compartment S, in the direction of the arrows 12, into the receiver. The steam generated in the section F passes from 5 the compartment Q to the receiver by the pipe V in the direction of the arrows 13.

The various fire-tubes and water-tubes are operatively connected to the caps and chambers by expanding them, or by any approved 10 screw-joints, nuts, or other suitable fastenings or connections. The water is heated gradually in its passage through the water-tubes, and over the fire-tubes, so that the steam is generated in a very effective manner. The tubes of sections F and G are 15 shown inclined in opposite directions, but they may be arranged in line with each other if desired.

In the modification shown in Fig. 3, the 20 two chambers *a* and *b* have respectively a grate *c* and a chimney *d*, and are separated by a partition the lower part of which is formed by the bridge-wall *e*. The two sections *f* and *g* of the boiler are arranged in the 25 chambers *b* and *a* respectively, and have fire-tubes *h* and water-tubes *i*. A single header 20 is arranged over the bridge-wall, and is provided with two partitions 21 and 22, which separate it into three compartments 30 23, 24, and 25. A receiver *u* is arranged over the header 20 and is connected to its compartments 24 and 25. The rear ends of the water-tubes of the section *f* are connected to and supported by a water-chamber 35 or header 30, and 31 is a pipe which connects the upper part of the header 30 with the water space of the receiver *u*. A plate *n* supports the front ends of the water-tubes of section *g*, and the water-tubes and 40 fire-tubes of this section *g* are provided with longitudinal partitions 8 in said water-tubes. The water-tubes *i* of section *f* are connected to the chamber 30 and to the compartment 23. The water-tubes of section *g* are 45 connected to the compartment 25, and they are provided with tubular connections 32 between their lower parts and the compartment 24. The fire-tubes *h* of both sections are continuous, and pass through the chamber 30 and the compartments 23, 24 and 25, their front ends being secured in the caps 50 6 of the water-tubes of the section *g*. The products of combustion pass from the grate in the direction of the arrows 10, through chamber *a*, the fire-tubes, and chamber *b*, to the chimney. The cold water enters the 55 lower part of compartment 23 by the pipe *y*, and passes through the water-tubes of section *f*, upward through chamber 30 and pipe 31, and the receiver, down the compartment 24 into the water-tubes of section *g*, in the direction of the arrows 11. The steam passes from the water-tubes of section *g* through the compartment 25 to the receiver in the direction of the arrows 13. Any 60 65

steam formed in section *f* passes through the pipe 31 into the receiver with the water.

In the modification shown in Fig. 4, the chambers *a'* and *b'* have respectively a grate *c'* and a chimney *d'*, and are separated by a partition the lower part of which is formed by the bridge-wall *e'*. The two sections *f'* and *g'* of the boiler are arranged in the chambers *b'* and *a'* respectively, and have fire-tubes *h'* and water-tubes *i'*. A single header 40 is arranged over the bridge-wall, and is provided with two partitions 41 and 42, which separate it into three compartments 43, 44, and 45. A receiver *u'* is arranged over the header 40 and is connected to the compartments 44 and 45. The rear ends of the water-tubes of section *f'* are connected to a water-chamber or header 50, the upper part of which communicates with the receiver by a pipe 51. A water-chamber or 85 header 52 communicates with and supports the front ends of the water-tubes of section *g'*, and this header 52 is connected with the water space of the receiver by a pipe 53. The water-tubes of section *f'* are connected 90 with the compartment 43; and the water tubes of section *g'* are connected with the compartment 45. The fire-tubes of both sections are continuous, and extend through the water-tubes and headers. The products 95 of combustion pass from the grate in the direction of the arrows 10, through the chamber *a'*, the fire-tubes, and chamber *b'*, to the chimney. The cold water enters the lower part of compartment 43 by the pipe 100 *y'*, and passes through the water-tubes of section *f'*, the header 50, receiver *u'*, pipe 53, header 52, into the water-tubes of section *g'*, in the direction of the arrows 11. The steam passes from the water-tubes of 105 section *g'*, through the compartment 45 to the receiver *u'*, in the direction of the arrows 13.

What I claim is:

1. In a boiler, the combination, with a 110 fire-chamber, and a smoke-chamber; of fire-tubes operatively connecting the said chambers, water-tubes encircling the said fire-tubes, and arranged in the said chambers in separate series, and means for circulating the water through the series of water-tubes in the said smoke-chamber and thence into the series of water-tubes in the said fire-chamber.

2. In a boiler, the combination, with a 120 fire-chamber, and a smoke-chamber; of fire-tubes operatively connecting the said chambers, water-tubes encircling the said fire-tubes and arranged in the said chambers in separate series, a receiver for steam and 125 water arranged above all the said tubes, a compartment operatively connecting the water-tubes in the fire-chamber with the steam space of the said receiver, and means for circulating the water through the series 130

of water-tubes in the said smoke-chamber and thence into the series of water-tubes in the said fire-chamber.

3. In a boiler, the combination, with a fire-chamber, and a smoke-chamber, said chambers being arranged side by side and separated by a partition: of fire-tubes which conduct the products of combustion through the said partition and which connect the front end portion of the said fire-chamber with the rear end portion of the said smoke-chamber, water-tubes encircling the said fire-tubes and arranged in the said chambers in separate series, and means for circulating the water through the series of water-tubes in the said smoke-chamber and thence into the series of water-tubes in the said fire-chamber.

4. In a boiler, the combination, with a fire-chamber provided with a grate at its lower part, and a smoke-chamber arranged to the rear of the said fire-chamber and provided with a chimney at its upper part; of fire-tubes operatively connecting the opposite end portions of the said chambers, water-tubes encircling the said fire-tubes and arranged in the said chambers in separate series, and means for circulating the water through the series of water-tubes in the said smoke-chamber and thence into the series of water-tubes in the said fire-chamber.

5. In a boiler, the combination, with a fire-chamber, a smoke-chamber, and an intermediate chamber, said chambers being separated by partitions; of fire-tubes connecting the said intermediate chamber with the front end portion of the said fire-chamber and with the rear end portion of the said

smoke-chamber respectively, water-tubes encircling the said fire-tubes and arranged in separate series in the said fire-chamber and smoke-chamber, and means for circulating the water through the series of water-tubes in the said smoke-chamber and thence into the series of water-tubes in the said fire-chamber.

6. In a boiler, the combination, with a fire-chamber, a smoke-chamber, and an intermediate chamber, said chambers being separated by partitions; of two headers which form portions of the said partitions, each of the said headers having two compartments, fire-tubes passing through the said headers and connecting the said intermediate chamber with the opposite end portions of the said fire-chamber and smoke-chamber, water-tubes encircling the said fire-tubes and arranged in separate series in the said fire-chamber and smoke-chamber, said water-tubes being operatively connected with the compartments of the headers pertaining to the said chambers, and means for circulating the water through the series of water-tubes in the said smoke-chamber and both compartments of the header connected to them and thence into one of the compartments of the other header and the water-tubes connected to it and arranged in the said fire-chamber.

In testimony whereof I have affixed my signature in the presence of two witnesses.

HANS O. KEFERSTEIN.
